FIG. 1

UNITED STATES PATENT OFFICE

2,276,754

MOTION CONTROLLING APPARATUS

Raymond E. Zenner, Brookfield, Ill., assignor to
Teletype Corporation, Chicago, Ill., a corpora-
tion of Delaware

Application November 13, 1939, Serial No. 304,059

13 Claims. (Cl. 178—27)

This invention relates to printing telegraph apparatus and particularly to page printers having the typing elements mounted on a carriage which travels across the page for printing message material in lines.

In printers of the kind described above, the carriage is moved step-by-step for character spacing by power driven means, and is returned to a beginning-of-line position by a rapid motion imparted by a spring which is wound or tensioned as the carriage is moved in the direction of printing successive characters.

An object of the invention is to counteract inertia effects of movable elements on the carriage developed incident to the return of the carriage to the beginning-of-line position and arrestment at that position.

Patent 1,904,164 granted April 18, 1933, to S. Morton et al., shows a printing telegraph receiving device well adapted to accommodate and be improved by the addition thereto of apparatus according to the present invention. The printer shown therein is a type bar page printer having the type bars supported in a carriage which travels on rails to and fro for character spacing and return to beginning-of-line position. Permutation code bars, which effect the selection of the type bars for actuation, are slidably supported by the carriage and the longitudinal disposition of these bars is in the direction of travel of the carriage. The carriage is advanced step-by-step for character spacing by a rack and pinion mechanism operated under the control of an escapement, the carriage return movement is imparted by a coiled spring contained in a drum which is connected to the carriage by a flexible link, and the carriage is arrested by a dashpot controlled yieldable stop lever. The return of the carriage is rapid, and as it is arrested, those of the permutation code bars which occupy such selective positions that they are capable of moving upon the carriage in the direction of carriage return movement, may tend to be moved to their other selective position due to inertia, and may possibly move to such other selective position. Also, any of the permutation code bars which occupy limit positions upon the carriage in the direction of return movement may resist effort of the receiving selector mechanism to shift them to their opposite limit position.

According to one embodiment of the present invention, pivoted counterbalance members are added to the carriage at the end toward which the code bars may tend to shift as the carriage is arrested, and these counterbalance members

swing due to their own inertia as the carriage is arrested and engage the code bars individually to oppose the forces tending to shift the code bars. The counterbalance members may be relatively heavily weighted so that their moments of inertia shall be sufficient to prevent movement of the code bars with respect to the carriage in the direction of carriage return movement even though the receiving selector mechanism should then be attempting to move any of them in that direction. Alternatively, the counterbalance members may be so weighted as to counterbalance exactly the forces acting upon the code bars due to inertia, thereby rendering the code bars as free to respond to control by the receiving selector mechanism as if the carriage were not subject to inertia forces.

According to another embodiment of the invention, a positive lock is provided for locking the code bars in either of their selective positions, the lock being rendered effective about the time that the carriage engages the dashpot controlled arresting lever and being released as the arrestment of the carriage is completed so that at all other times the locking mechanism has no effect upon the permutation code bar.

For a complete understanding of the present invention, reference may be had to the following detailed description which refers to the accompanying drawing wherein:

Fig. 1 is a front elevational view of the type bar carriage and related controlling apparatus according to the disclosure of the hereinbefore identified patent, with the device according to one embodiment of the present invention added thereto;

Fig. 2 is a detailed perspective view of the code bar counterbalance device according to the present invention; and

Fig. 3 is a view similar to Fig. 1 showing the embodiment of the invention which involves locking rather than counterbalancing the code bars.

Referring now to the drawing, and particularly to Fig. 1, the reference numeral 11 designates the front rail of a pair of rails extending transversely of the printer disclosed in the hereinbefore identified patent in parallelism with the platen of the printer. Rails 11 support a type bar carriage 12 by means of rollers 13 revolvably supported on axle studs 14 secured to the carriage 12. Carriage 12 pivotally supports type bars 16 to each of which is articulated a combined selector and pull bar 17. Type bars 16 normally arrest against backstop 18.

The type bars 16 and selectable pull bars 17 are disposed in arcuate arrangement and the carriage 12 slidably supports upon studs 19 a set of notched permutation code bars 21 which are conformed to the arcuate alignment of the selectable pull bars 17. Apertures (not shown) in the code bar 21, through which studs 19 extend, are elongated so that the bars 21 may be moved endwise back and forth from one to the other of two possible positions. The permutational notching of the code bars 21 is such that for each permutational setting of the bars, not more than one of the selectable pull bars 17 finds presented to it an alignment of notches which it may enter.

Near its opposite ends, carriage 12 is provided with depending arms 22, one of which is short and the other is relatively long, the arms 22 having integral therewith at their free ends a connecting bar 23 which extends obliquely with respect to the bars 11 which support carriage 12. An arm 24 also integral with the long arm 22 at its free end extends leftwardly substantially parallel with rail 11.

The obliquely extending bar 23 pivotally supports a plurality of code bar operating bell cranks 26 which are equal in number to the number of code bars 21 and which have the free ends of their upwardly extending arms articulated individually to the code bars. Horizontally extending arms of the bell cranks 26 have their free ends bifurcated and fitted over the outer edges of individual pivoted selector vanes 27 so that the horizontally extending arms of bell cranks 26 may move along and remain in engagement with selector vanes 27 as carriage 12 travels to and fro upon rail 11, and bell cranks 26 may be rocked as selector vanes 27 are controlled by the receiving selector mechanism of the printer in the manner fully disclosed in the hereinbefore identified patent. When bell cranks 26 are rocked clockwise or counterclockwise by selector vanes 27, they impart rightward or leftward movement to the permutation code bars 21, thus positioning them permutatively for the selection of individual selectable pull bars 17. A retaining bar 28 extends from the lower end of the shorter of the two arms 22 to the free end of arm 24 and confines the horizontally extending arms of bell cranks 26 so that they shall remain in engagement with selector vanes 27.

As shown in Fig. 1, there are six of the bell cranks 26, each being connected to one of the selector vanes 27 and also to one of the permutation code bars 21. It follows from this that the particular printer shown in Fig. 1 has six code bars 21 and operates on a six-unit code. In the printer shown in the hereinbefore identified patent, there are five of these bell cranks which indicate that the printer operates on a five-unit code and is provided with five selecting code bars. The number of bell cranks 26 and code bars 21 provided in a printer depends upon the number of selective possibilities for which provision must be made. The present invention is applicable to printers operating on a five-unit code, as exemplified in the Morton et al, patent, or in a printer operating upon a six-unit code, as exemplified in Fig. 1, but the need of the invention may be greater in the case of a six-unit printer than of a five-unit printer, as will be set forth hereinafter.

At the left-hand side of the printer, a fixed post 31 supports a bracket 32 on which is pivoted a stop lever 33 for the carriage 12. The carriage 12 supports an adjustable abutment screw 34 in alignment with the foremost end of arm 33. As

carriage 12 moves leftwardly and approaches its beginning-of-line position, screw 34 engages the foremost end of lever 33 and moves it leftwardly. As fully disclosed in the hereinbefore identified patent, the rearmost end of stop lever 33 is connected to the plunger of a dashpot which establishes a limit for the leftward movement of carriage 12 by limiting the rocking movement imparted to lever 33, and which cushions the operation of lever 33 in arresting carriage 12.

At the left-hand side of carriage 12, a bracket 36 is secured to the carriage by mounting screws 37 which pass through horizontally extending elongated slots 38 (Fig. 2). Bracket 36 has secured thereto a pivot stud 39, an anchoring stud 41, and a backstop stud 42. Pivot stud 39 pivotally supports a plurality of counterbalance members 43 between each two of which is a spacer plate 44 jointly supported by pivot stud 39 and anchoring stud 41, so that the spacer plates 44 cannot rotate. Between the innermost counterbalance member 43, and the bracket 36, is an inner retaining plate 46 and similarly between the outermost or foremost of the counterbalance members 43 and the head 41 of pivot stud 49 is a retainer plate 48 (Fig. 1), the plates 46 and 48 being similar to the spacer plate 44 and similarly anchored upon stud 41.

The spacing of counterbalance members 43 on stud 39 is the same as the spacing of code bars 21 and the slots 38 permit bracket 36 to be adjusted so as to align counterbalance members 43 with the code bars 21. Each of the counterbalance members 43 has at its upper end a projection 49 presented in close proximity to the left-hand end of the code bar 21 with which it is aligned. The projections 49 are so positioned and dimensioned that when the counterbalance members 43 are suspended motionless in engagement with backstop stud 42, the projections 49 will not engage the ends of code bars 21 whether those bars are presented in their extreme left-hand or right-hand selective positions.

When carriage 12 moves leftwardly, as viewed in Fig. 1, to return to the beginning-of-line position, the counterbalance members 43 engage backstop stud 42 and, therefore, their projections 49 are held clear of code bars 21. The velocity of carriage 12 as its abutment screw 34 engages dashpot controlled lever 33 may be relatively high, and the arrestment of the carriage by yielding lever 33 may subject the code bars 21 to forces generated by the inertia of the bars and tending to move them leftwardly, as viewed in Fig. 1. At the same time that the forces are generated in code bars 21, forces are also generated in the counterbalance members 43 causing them to pivot clockwise, as viewed in Fig. 1, about pivot stud 39, and causing their projections 49 to engage or seek engagement with the left-hand ends of code bars 21.

The counterbalancing of code bars 21 by counterbalance members 43 may be arranged to satisfy various conditions. For example, it may be desired to cause counterbalance members 43 to exert upon all of the code bars 21 considerably greater force than that which tends to move the code bars 21 leftwardly. This may be accomplished by weighting the counterbalance members 43 rather heavily at their lower ends and by having the ends of projection 49 very close to the ends of the code bars 21 when those bars are presented in their left-hand position, so that each code bar shall be positively and firmly engaged by its counterbalance member 43. With

this arrangement, movement of the code bars 21 by any forces which might be exerted upon them, such as, by their own inertia or by the receiving selector mechanism of the printer, would be prevented.

It may, under some circumstances, be found desirable to weight the counterbalance members 43 just sufficiently to overcome forces produced by inertia alone tending to move the code bars 21 leftwardly. It may be ascertained by reference to the hereinbefore identified patent that the printer disclosed therein operates with a condition of overlap. By this is meant that as soon as the receiving selector mechanism has completed one selective cycle, and while the printer is operating in accordance with the signal received during that selective cycle, whether the operation involves the printing of a character, spacing of the carriage, or the performance of a function, such as carriage return, the receiving selector mechanism may be released for the reception of the next signal combination and may operate to set up in itself the selective condition corresponding to the signal. Certain locks are provided or are inherent in the printer to limit the shifting of the code bars 21 under the control of the selector vanes 27 to certain definite times with reference to the operation of the receiving selector mechanism. The use of such locks is predicated upon the fact that printing operations, and most of the function operations, require a known and invariable time for their accomplishment. Carriage return function differs from the other functions in that the time elapsing between the initiation of the carriage return function and the arrestment of the carriage is a variable, depending upon the distance through which the carriage must travel to reach its beginning-of-line position. Thus, it may happen that at the instant that lever 33 is arresting carriage 12 at the beginning-of-line position, the code bars are unlocked and the receiving selector mechanism is attempting to impart a selective setting to one or more of the code bars 21 through the selector vanes 27 and bell cranks 26. Movement of any of the code bars 21 to their left-hand position presents no difficulty at this time as the energy generated by the inertia of the code bars is added to the energy supplied by the receiving selecting mechanism for shifting the code bars 21. Should the receiving selector mechanism be attempting to shift any of the code bars 21 to their extreme right-hand position at the time of arrestment of carriage 12 a different situation exists. The inertia of code bars 21 may prevent the receiving selector mechanism from shifting the code bars to the right. In order to give the receiving selector mechanism full control over the code bars 21, the inertia members 43 may be so weighted as to counterbalance exactly the forces tending to maintain the code bars in their extreme left-hand position. With this arrangement, the receiving selector mechanism would be as effective to shift the code bars 21 to the left as when the carriage 12 is stationary.

In connection with the weighting of the counterbalances, it should be noted that other elements than the code bars are subject to inertia and may add their effect to that of the code bars. The upwardly extending arms of the bell cranks 26 are movable pivotally in the direction of movement of the carriage, and are subjected to forces caused by inertia and tending to rock them coun-

terclockwise. These forces may supplement those developed in the code bars themselves, and may necessitate counterweighting the code bars more heavily than would be required to overcome the inertia effects of the code bars alone.

It should be noted in connection with structures requiring merely the exact counterbalancing of the code bars to permit them to be shifted to their right-hand positions without interference due to inertia effects, that only certain ones of the code bars, such as the fourth or fifth in the case of printers operable upon the five-unit code, or the fifth or sixth in the case of printers operable upon the six-unit code, could be under the direct influence of the receiving selector mechanism at the time of arrestment of carriage 12. This is because of the fact that the early impulses of the code combination received in overlap relation to the carriage return function would be received before the release of the carriage for return to its beginning-of-line position or before it has traveled any great distance. Where the carriage travels through only a very short distance in reaching its position of arrestment, the forces generated due to inertia would have no adverse effect upon the control of the code bars by the receiving selector mechanism. From this, it will be apparent that the counterbalancing might be needed only in connection with those code bars which the receiving selector mechanism might be trying to shift to their right-hand positions after the carriage had traveled a sufficient distance to develop inertia forces of consequence. This could occur only near the end of the signal combination received in overlap relation to the carriage return operation, and it might, therefore, be necessary to counterbalance only one or two of the code bars, these being the bars which the receiving selector mechanism might be attempting to set at a time when the inertia effects of the code bar can be greatest. The possibility that code bars may need to be counterbalanced to permit selective setting of them during carriage arrestment may be greater in the case of the printer operating on the six-unit code, because six selective conditions must be established instead of five, a smaller fraction of the receiving cycle is allotted to each selective condition, and the last selective condition is established later in the cycle.

Another embodiment of the invention is shown in Fig. 3. It is applicable to the same kind of printing telegraph apparatus shown in Fig. 1, and the type bar carriage and all associated apparatus has been identified by the same reference numerals as in Fig. 1.

The carriage 12 has mounted thereon a pivot pin 61 on which is pivotally mounted a lock lever 62 biased in clockwise direction by tension spring 63. Lock lever 62 has lock bar 64 at the upper end thereof spanning the code bars 21. Each of the code bars 21 is provided with two notches 66 on the lower edge thereof, one of which is aligned with lock bar 64 when a code bar is in one of its selective positions, and the other of which is aligned with the lock bar when the code bar is in the other of its selective positions. Lock lever 62 is normally held out of engagement with the notches 66 of code bars 21 by a latch 67 pivoted on carriage 12 by means of pivot pin 68 and having its hook-shaped end 69 urged into retaining engagement with pin 71 of lock lever 62 by tension spring 72.

The front rail 11 has extending forwardly therefrom, below the portion engaged by rollers

13, pins 73 and 74. Pin 74 is short enough to permit the lower end of lock lever 62 to pass in front of its free end as the carriage 12 travels rightwardly for character spacing, or leftwardly for character return. Pin 74 is, however, disposed in the path of a depending arm 76 pivoted to latch 67 at 77 and having a stop lug 78 engageable with the right-hand side of latch 67 for causing arm 76 to impart counterclockwise movement to latch 67 when arm 76 engages pin 74 upon approaching the pin from the right, which is the direction of approach when carriage 12 is returning to the beginning-of-line position. When arm 76 engages pin 74 upon approaching from the left, it yields and rocks idly in clockwise direction with respect to latch 67, the lug 78 moving out of engagement with the left-hand side of latch 67 until arm 76 has cleared pin 74, whereupon arm 76 returns to the position with respect to latch 67 shown in Fig. 3. Pin 73 is of sufficient length to extend into the path of the lower end of lock lever 62 so that when the lock lever engages pin 73 as carriage 12 travels leftwardly, counterclockwise movement with respect to carriage 12 will be imparted to lock lever 62 to withdraw its locking bar 64 out of the notches 66 of code bars 21.

Pin 74 is so positioned on rail 11 that it becomes engaged by arm 76 of latch 67 about the time that abutment screw 34 of carriage 12 comes into engagement with yieldable stop arm 33, and upon engagement of arm 76 with pin 74 continued movement of carriage 12 leftwardly causes latch 67 to pivot counterclockwise and to become disengaged from pin 71 of lock lever 62. Lever 62 thereupon responds to its tension spring 63 and its locking bar 64 enters one or the other of the two notches 66 in each code bar 12 to lock them against movement. By virtue of the counterclockwise pivotal movement of latch 67, its depending pivoted arm 76 is enabled to pass over the top of pin 74 and spring 72 attempts to restore latch 67 to the position shown in Fig. 3, but pin 71 is then outside the shoulder of hooked end 69 of latch 67 and blocks latch 67. Pin 73 is so positioned on rail 11 that just before the arrestment of carriage 12 is completed, pin 73 will be engaged by the lower end of lock lever 62 and sufficient counterclockwise movement will be imparted to lock lever 62 due to the leftward movement of carriage 12 to withdraw locking bar 64 from engagement with the notches 66 and to relatch pin 71 of lock lever 62 behind the shoulder of the hooked end 69 of latch 67. Thus, the code bars will have been positively locked against movement by the receiving selector mechanism, or due to inertia, just before the operation of arresting the carriage begins, and they will be unlocked just before the carriage becomes fully arrested. When carriage 12 moves rightwardly for character spacing, depending pivoted arm 76 of latch 67 passes over the top of pin 74 by rocking idly without imparting any movement to latch 67 and returns to the position shown in Fig. 3 prepared to operate latch 67 to unlatch locking lever 62 upon the next carriage return movement of the carriage 12.

Although specific embodiments of the invention have been described in the foregoing specification and shown in the accompanying drawing, it is to be understood that the invention is not limited to such specific embodiments but is capable of modification and rearrangement without departing from the spirit of the invention and within the scope of the appended claims.

What is claimed is:

1. In a printing telegraph apparatus, a type bar carriage movable for character spacing and returnable to a beginning-of-line position, a plurality of type bar selecting code bars extending in the direction of movement of said carriage and slidably supported thereby, means for arresting said carriage at the beginning-of-line position, and means including an element cooperating with said code bars for preventing movement of said code bars due to their inertia as said carriage is arrested.

2. In a printing telegraph apparatus, a type bar carriage movable for character spacing and returnable to a beginning-of-line position, a plurality of type bar selecting code bars extending in the direction of movement of said carriage and slidably supported thereby, means for arresting said carriage at the beginning-of-line position, and means including a yieldably mounted element co-operating with said code bars for resisting movement thereof relative to said carriage due to their inertia as said carriage is arrested.

3. In a printing telegraph apparatus, a typing carriage movable for character spacing and returnable to a beginning-of-line position, a plurality of selector bars slidable endwise upon said carriage in the direction of movement thereof, means for selectively positioning said bars, means for arresting said carriage at the beginning-of-line position, and means including a pivotally mounted element co-operating with said selector bars for opposing movement thereof relative to said carriage due to their inertia as said carriage is arrested while permitting said bars to be moved by said positioning means.

4. In a printing telegraph apparatus, a typing carriage movable for character spacing and returnable to a beginning-of-line position, a plurality of selector bars slidable endwise upon said carriage in the direction of movement thereof, means for arresting said carriage at the beginning-of-line position, and means operable by inertia as said carriage is arrested for engaging said selector bars and opposing movement thereof relative to said carriage due to their inertia.

5. In a printing telegraph apparatus, a typing carriage movable for character spacing and returnable to a beginning-of-line position, a plurality of selector bars slidable endwise upon said carriage in the direction of movement thereof, means for arresting said carriage at the beginning-of-line position, and means individually engageable with each of said bars by inertia as said carriage is arrested for opposing movement of said bars relative to the carriage due to the inertia of said bars.

6. In a printing telegraph apparatus, a typing carriage movable for character spacing and returnable to a beginning-of-line position, a plurality of selector bars slidable endwise upon said carriage in the direction of movement thereof, means for moving said bars upon said carriage including portions mounted on said carriage and movable in the same direction as said bars, means for arresting said carriage at the beginning-of-line position, and means operable by inertia as said carriage is arrested for counter-balancing inertia of said bars and the portions of said bar moving means movable in the same direction as said bars.

7. In a printing telegraph apparatus, a typing carriage movable for character spacing and re-

turnable to a beginning-of-line position, a plurality of selector bars slidable endwise upon said carriage in the direction of movement thereof for controlling typing operations of said typing carriage, means for arresting said carriage at the end-of-line position, and inertia operable means pivotally mounted upon said carriage and engageable with an end of each of said bars as said carriage is arrested for counter-balancing inertia of said bars.

8. In a printing telegraph apparatus, a typing carriage movable for character spacing and returnable to a beginning-of-line position, a plurality of selector bars slidable endwise upon said carriage in the direction of movement thereof for controlling typing operations of said typing carriage, means for arresting said carriage at the beginning-of-line position, and means for locking said bars against movement due to inertia as said carriage is arrested.

9. In a telegraph apparatus, a typing carriage movable for character spacing and returnable to a beginning-of-line position, a plurality of selector bars slidable endwise upon said carriage in the direction of movement thereof for controlling typing operations of said typing carriage, means for arresting said carriage at the beginning-of-line position, means rendered effective just before said carriage arrives at said beginning-of-line position for locking said bars against movement due to inertia, and means effective as said carriage reaches said position for disabling said locking means.

10. In a telegraph apparatus, a typing carriage movable for character spacing and returnable to a beginning-of-line position, a plurality of selector bars slidable endwise upon said carriage in the direction of movement thereof for controlling typing operations of said typing carriage, means for arresting said carriage at the beginning-of-line position, means for locking said bars against movement with respect to said carriage, means normally holding said locking means in ineffective position, means engaged by said holding means shortly before arrestment of said carriage for disengaging said holding means from said locking means whereby to render said locking means effective, and means engaged by said locking means as said carriage reaches said 50

beginning-of-line position for re-engaging said locking means with said holding means.

11. In a printing telegraph apparatus, a typing carriage movable for character spacing and returnable to a beginning-of-line position, a plurality of selector bars slidable endwise upon said carriage in the direction of movement thereof for controlling typing operations of said typing carriage, yieldable means for arresting said carriage at the beginning-of-line position, means for cushioning the motion of said arresting means, means for locking said bars against movement with respect to said carriage, means normally holding said locking means in ineffective position, means engaged by said holding means substantially when said carriage engages said yieldable arrestment means for disengaging said holding means from said locking means whereby to render said locking means effective, and means engaged by said locking means substantially as said yieldable means completes the arrestment of said carriage for re-engaging said locking means with said holding means.

12. In a printing telegraph apparatus, a type bar carriage movable for character spacing and returnable to a beginning-of-line position, a plurality of type bar selecting code bars extending in the direction of movement of said carriage and slidably supported thereby, means for arresting said carriage at the beginning-of-line position, and means including an element individual to each of said code bars normally disassociated from said code bars for co-operating therewith to resist movement thereof relative to said carriage due to their inertia as said carriage is arrested.

13. In a printing telegraph apparatus, a type bar carriage movable for character spacing and returnable to a beginning-of-line position, a plurality of type bar selecting code bars extending in the direction of movement of said carriage and slidably supported thereby, means for arresting said carriage at the beginning-of-line position, means for preventing movement of said code bars due to their inertia as said carriage is arrested, and means for supporting said last recited means relative to said code bars whereby said means is effective on said code bars upon the arrestment of said carriage.

RAYMOND E. ZENNER.
